LADY'S CAP

Lois H. Stonestreet, Charlotte, N. C., assignor to
Kwik-tite, Incorporated, Charlotte, N. C., a corporation of North Carolina

Application February 16, 1950, Serial No. 144,531

3 Claims. (Cl. 2—198)

1

This invention relates to a lady's cap and more particularly to a cap which may completely cover the hair of the wearer and which provides an attractive cap which may be simply and economically constructed.

It is an object of this invention to provide a lady's cap which may be worn in two different ways and may be used for a multitude of purposes. The cap may be made of water-proof material, such as plastic, or of any suitable fabric and may be used in any number of ways as for example as a rain cap or as a nurse's cap which completely encloses the hair of the wearer.

It is another object of this invention to provide a cap having an irregularly shaped body portion having extensions on each side thereof to form triangularly shaped tabs and having tie members on the ends of these triangularly shaped tabs and also having a front portion of the cap secured to the irregularly shaped body portion and extending to a point adjacent the point where the triangularly shaped tabs begin and this front portion also being provided with a pair of tie straps, to permit the body portion and the front portion of the cap to be placed over the hair of the wearer so that the two pairs of straps may be tied around the cap to hold the same securely in position.

It is another object of this invention to provide a cap of the type described having two pairs of tie straps so that, if desired, the lower pair of tie straps may be tied around the head of the wearer with the cap extending behind the wearer and then the body of the cap may be pulled up over the head of the wearer and the other tie straps may then be tied around the cap to completely enclose the hair of the wearer.

It is still another object of this invention to provide a cap having two pairs of tie straps on each side thereof and whereby one pair of said straps may be provided with suitable snap fasteners on the ends thereof to assist in holding the cap securely in position.

Some of the objects of the invention having been stated, other objects will appear as the description proceeds, when taken in connection with the accompanying drawings, in which:

Figure 1 is a top plan view of the cap;

Figure 2 is a view similar to Figure 1 but showing a slightly modified form of cap;

Figure 3 is an enlarged vertical sectional view taken along the line 3—3 in Figure 1 and showing the manner in which the front portion of the cap is secured to the main body portion.

Figure 4 is an enlarged vertical sectional view taken along the line 4—4 in Figure 2 and showing the manner in which the lower portion of the cap is constructed;

Figure 5 is an enlarged view of the area outlined in dotted lines in Figure 2 showing the

2

manner in which the front portion of the cap joins the body portion of the cap adjacent the two tie straps;

Figure 6 is an enlarged vertical sectional view taken along one line 6—6 in Figure 5;

Figure 7 is a perspective view of the cap shown in Figure 1 showing one way in which it may be attached to the head of a wearer;

Figure 8 is a perspective view of the cap shown in Figure 7 with the body portion thereof over the head of the wearer;

Figure 9 is a front perspective view of the cap as shown in Figures 7 and 8 tied in position on a lady's head;

Figure 10 is a rear perspective view of the cap shown in Figure 2 placed on the head of a wearer;

Figure 11 is a front perspective view of the cap shown in Figure 10 and showing the same snapped in position and completely covering the hair of the wearer.

Referring more specifically to the drawings, there will be observed a cap broadly designated at 10 having a body portion 11 which is irregularly-shaped and which has extensions on each side of the lowermost edge thereof forming two triangularly-shaped tabs 12 and 13. The outer edges of the tabs 12 and 13 are enclosed by tapes 15 and 16 secured thereto by lines of stitches 17 and 18 and by a line of stitches 28 to be presently described.

A tape 20 binds the lower edge of the body 11 as by stitches 21 and 21a with centrally located gathers 35 which define the adjacent outer edges 35 of triangular tabs 12 and 13 and the tape 20 extends from the juncture of the two outer edges of each tab to form lower tie straps 22 and 23.

The inner edge portion of the body 11 is folded over as at 25 and the turned under portion 26 of a somewhat crescent-shaped front piece 27 is secured thereto as by the stitches 28 which also secure the tapes 15 and 16 to the tabs 12 and 13. The inner edge of the front piece 27 is of substantially the same configuration as the inner edge of the upper portion of the body portion 11 to which it is sewn, and the front piece 27 is cut away along its outer edge so that the outer edge of the front piece 27 is substantially U-shaped in plan. The opposite ends of the front piece 27 extend to a point adjacent the tab portions 12 and 13. The front piece 27 thus conforms to the curvature of the head of a wearer.

This outer edge of the front piece 27 has a tape 30 folded over and secured thereto as by stitches 31 and 32 (Figure 3) and the tape 30 extends beyond each end of the front piece 27 at the juncture of the tabs with the body portion to form upper tie straps 33 and 34.

Each end of the front piece 27 has a portion 36 which is turned under, the turned under por-

tion 36 being of substantially the same configuration as that part of the front piece which covers it, but of slightly lesser width. Only the portion 36 at the right-hand side of the cap is shown in Figures 2 and 5, and this turned under portion 36 is secured to the body 11 by the lines of stitches 18 and 28 which also secure the tape 16 to the tab 13 (Figure 6) and the turned under portion 36 and is also held in place by the line of stitches 31 securing the tape 30 to the front piece 27.

The lower central portion of the body 11 is gathered as at 35 and is held in place by the stitches 21 and 21a to cause the cap to conform more nearly to the shape of the head of the wearer.

Referring to Figure 2 there will be observed a slightly modified form of the cap broadly indicated at 10'. As the cap 10' is of substantially the same structure as the cap 10 with the modifications to be noted, the same reference characters will apply to both caps. Now referring to Figure 2 it will be observed that tie straps 22' and 23' are provided and these straps 22' and 23' are of substantially shorter length than the straps 22 and 23 in the original form of the invention. Snap fastener elements 40 and 41 are suitably secured to the end of the tie straps 22' and 23' and the upper portion of the front piece 27 or the binding tape 30 is provided with spaced snap fastener elements 42 and 43 adapted to be engaged by the snap fastener elements 40 and 41 when the cap is secured on the head of the wearer as shown in Figure 10.

It should be noted that although two forms of the cap are shown either form of the cap may be worn in the two different ways, to be presently described, and the modification is not necessary to permit the cap to be worn in two different ways.

Referring now to Figures 7, 8 and 9, it will be observed that the cap 10 may be worn by placing the tie straps 22 and 23 around the head of the wearer and underneath the hair and tying these straps together at the top of the head as at 45. The body 11 of the cap may then be placed in position over the head of the wearer so that the tape 30 will be positioned across the upper forehead of the wearer and the upper tie straps 33 and 34 may be tied together behind the head of the wearer so that the cap will appear as shown in Figure 9. When the cap is worn in this manner the hair of the wearer will be almost but not completely covered.

Now if it is desired to completely cover all of the hair of the wearer as may be required of nurses for example, the hat may be reversed so that the body 11 is placed over the head of the wearer with the tape 30 on the forehead of the wearer and then the upper tie straps 33 and 34 may be tied behind the head of the wearer and the tabs 12 and 13 may be placed on either side of the head of the wearer and the lower tie straps 22 and 23 may be tied around the front of the cap and the forehead of the wearer, or if it is desired to use the modified form of cap 10', the straps 22' and 23' may be placed as shown in Figure 10 so that the snap fastener elements 40 and 41 will engage the snap fastener elements 42 and 43 to hold the cap securely in position.

It is thus seen that I have provided an improved lady's cap which may be worn either as a rain cap or as any other type of decorative cap or which may be alternately worn as a nurse's

cap to completely enclose the hair of the wearer. It is also seen that I have provided a cap which is extremely neat in appearance and may be very simply and economically constructed and which may be worn in two different ways and for a number of different purposes.

In the drawings and specification there has been set forth a preferred embodiment of the invention, and although specific terms are employed, they are used in a generic and descriptive sense only, and not for purposes of limitation, the scope of the invention being defined in the claims.

I claim:

1. A lady's cap having an irregularly-shaped body portion having triangularly-shaped integral tabs extending from the lowermost edge thereof, said cap also being provided with a somewhat crescent-shaped front piece secured to the edge of the upper portion of the body portion and having its opposite end portions extending to a point adjacent the juncture of the triangularly-shaped tabs with the body portion, said front piece having upper tie straps secured thereto and extending one from each end thereof adjacent said juncture and each of said triangularly-shaped tabs having a lower tie strap secured to and extending from the juncture of the outer edges of each tab.

2. A lady's cap having an irregularly-shaped body portion having a pair of triangularly-shaped integral tabs extending from the lowermost edge thereof, said cap also being provided with a somewhat crescent-shaped front piece having its inner edge secured to the edge of the upper portion of the body portion and having its opposite end portions extending to a point adjacent the juncture of the triangularly-shaped tabs with the body portion, the outer edge of said front piece being substantially U-shaped, upper straps secured to said front piece and extending from each end thereof adjacent said juncture and said triangularly-shaped tabs having lower straps secured to and extending from the juncture of the outer edges of each tab.

3. In a cap, a body portion and a somewhat crescent-shaped front piece having its inner edge secured to the edge of the upper portion of the body portion, said body portion having a pair of integral tabs extending from the lowermost edge thereof, said tabs being provided with snap fastener elements at their ends remote from said body portion, said front piece having an outer edge of a configuration to conform to the head of a wearer and having a tie strap extending from each of the opposite ends thereof, said front piece also being provided with spaced snap fastener elements on the outer edge adjacent the center thereof adapted to mate with the snap fastener elements on said tabs.

LOIS H. STONESTREET.
